BY
Henry J. Lueke,
HIS ATTORNEY.

UNITED STATES PATENT OFFICE

CLARENCE E. PRYOR, OF ELIZABETH, NEW JERSEY

COMBINED SNAP AND TESTING SWITCH FOR FLASHLIGHTS

Application filed January 12, 1931. Serial No. 508,173.

This invention relates to a combined snap and testing switch for flash lights.

The invention resides in a switch for flash lights serving primarily as a snap switch, in substitution of the regulation snap switch, which is usually disposed on the cylindrical side of the casing which encloses the dry cells.

Pursuant to the invention, my snap switch 10 is located at the end of the casing, and preferably within the end cap of the casing. The end cap is formed of electrically conducting material and with or without insulation as appears more fully hereinafter.

15 The construction of my snap switch adapts it also for testing fuses of all types, electric lamp bulbs, and other electrical devices, attachments, etc., which are suitably dimensioned to the flash light casing.

20 A preferred form of my invention embodies a length of spring wire member having its one end projecting exteriorly of the flash light casing, preferably through a slot in the end cap, the inner portion of the wire 25 extending spirally or otherwise within the casing and covered with electrically insulating tubing or otherwise suitably insulated, an inner portion of the cap or wire member being exposed and located to engage the bottom of the casing of a cell or cells serving 30 as the source of electrical energy.

Cooperating with such wire member, I provide suitable means for receiving and retaining the exterior end of the wire member to 35 locate its exposed portion in electrical contact with the end cap or otherwise with the electrically conducting flash light casing, to thereby effect the closure of the electrical circuit through the lamp of the flash light.

40 Suitable means are also provided for receiving and holding the wire member to locate its outer end exposed portion out of electrical contact with the flash light casing, for the open-circuit position of the switch.

45 To check-up the integrity of fuses, electric bulbs, etc., one terminal of such article is placed in electrical engagement with the exposed portion of the exterior end of the switch member, the switch member being in 50 its open-circuit position and the other ter-

55 minal brought into electrical engagement with the end cap or exposed portion of the flash light casing, in which circumstances the electric lamp of flash light is lighted under the condition of integrity of the tested article and unlighted under the condition of non-integrity of the tested article.

Further features and objects of the invention are more fully understood from the following detail description and the accompanying drawings, in which

Fig. 1 is a side elevation, partly broken away in central section, illustrating a flash light equipped with my cap and snap switch. Fig. 1 also indicates in dot-and-dash outline 65 an electrical fuse in position for testing, the switch member being in its open-circuit position.

Fig. 2 is a top plan view of Fig. 1.

Fig. 3 is a detail sectional elevation on line 3-3 of Fig. 1, the movable switch member being however moved to its closed-circuit position.

Fig. 4 is a detail sectional elevation on line 4-4 of Fig. 2, the switch member however being shown in its open-circuit position.

Fig. 5 is a view similar to Fig. 4 but illustrating a modification of construction of the switch member and its open-circuit and 80 closed-circuit retaining means;

Fig. 6 is a central sectional view of the upper portion of Fig. 5, showing the switch member in its closed-circuit position.

Fig. 7 is an elevational view of the inner 85 face of my cap, showing a further modification; and

Fig. 8 is a plan view of the exterior of the cap of Fig. 7.

The flashlight is illustrated of the conventional design of substantially cylindrical casing 10 within which the one or more electric cells 11 are enclosed, the bottom of each cell casing being of exposed electrically conducting material. The lamp bulb is indicated at 12, removably mounted in the usual socket support 13, at the center of the mirrored concave metal disc 14. The lens is indicated at 15.

My cap and snap switch is shown installed 100

at the opposite or lower end of the flashlight casing 10, and is most conveniently embodied in an end cap 16 of metal similar to regulation end caps but arranged to coordinate with 5 my invention.

My cap and snap switch comprises in general a movable switch member formed in whole or at least in part of spring metal such as brass wire, etc., the outer end of which 10 extends exteriorly of the end cap 16, the intermediate portion being disposed within the flashlight casing and suitably electrically insulated therefrom, the inner terminal or portion adjacent thereto being exposed for electrical contact under pressure with the bottom of the cell casing. The exterior end is exposed in whole or in part and suitable co-operating means are provided whereby the exposed wire of the exterior end is held in 20 electrical engagement with the metal of the end cap for the closed-circuit position of my switch, and retained in its open-circuit position to position and hold the exposed end of the movable wire switch member out of electrical contact with the metal of the flashlight casing.

In the drawings I have illustrated two forms of my cap and switch member, one form appearing in Figs. 1-4 and the other 30 form in Figs. 5 and 6.

In the form of my invention illustrated in Figs. 1-4, the end cap 16 is slotted as indicated at 17 to afford the projection therethrough of the exterior end 18 of the movable 35 wire member 19 of my switch, the intermediate portion of the wire member being illustrated as constituted of the rectilinear portion 19a extending from exterior end 18 to the bend 19b and further of the spirally coiled 40 or equivalent portion 19c, its inner terminal 20 being arranged to electrically engage under pressure with the bottom of the lowermost cell 11 or a single cell, as the case may be.

45 Such intermediate portions 19a, 19c are electrically insulated from the metal of the end cap 16 and of the metal of the flashlight casing 10 as by means of electrical insulating or tubing popularly known as spaghetti, or 50 other suitable insulating material, the inner terminal 20 being exposed in whole or in part to effect the above stated electrical engagement. The retaining means for the closed-circuit and open-circuit positions of the terminal portion 18 of my movable wire member 55 in the form illustrated in Figs. 1-4, comprises the disc 21 of insulating fibre or like suitable material which is molded or otherwise shaped to provide the locking lug 22, 60 see Figs. 1, 3 and 4, whereby when the exterior end 18 and portion 19a of my movable wire switch member is in engagement with the lug 22, see Figs. 1 and 4, the switch member is held in its open-circuit position, and 65 upon release from said lug 22, the resiliency

of the wire switch member effects electrical contact under pressure of the metal of the wire at the exposed portion of its end 18 with the metal of the end cap 16, for its closed-circuit position, as illustrated in Fig. 1, whereby 70 the circuit from the cell or cells through the wire member 19 is completed through such pressure contact, thence through the end cap 16, the metal of the flashlight casing 10, the metal disc 14, and thence to the outer terminal of the lamp bulb 12. To provide for the resilient effect or fulcrum for the movable wire switch member 19, the disc 21 is notched at a suitable location, see 25, usually substantially opposite to the location of the slot 17 in the end cap 16, the bend 19b of the movable wire switch member 19 being received therein, the insulated spiral or other contoured intermediate portion, 19c of the wire switch member frictionally engaging the end cap 16 or otherwise to be substantially retained in fixed relation relative to the end cap 16.

The arrangement set forth in Figs. 5 and 6 corresponds generally to that illustrated in Figs. 1-4 and like parts are designated by like reference characters. However, the movable wire switch member 19 is offset as indicated at 19d for cooperation with two notches or equivalent in the disc 21, one notch 26 for receiving the offset 19d to hold the wire switch member 19 in its open-circuit position, that is to say, to retain the exposed portion of its exterior end 18 out of contact 100 with the metal of the end cap 16, and the other notch 27 freely receiving the offset portion 19d to permit the exposed portion of the exterior end 18 to engage under pressure to electrically contact, say at the edge 21a, with the metal of the end cap 16 and therewith with the metal of the flashlight casing 10, for the closed-circuit position of the switch.

If desired, the switch retaining means may be constructed to positively hold the movable switch member in its closed-circuit position, in lieu of or in cooperation with the resiliency effect of the material of the wire switch member, to effect the necessary pressure for electrical engagement at its closed-circuit position.

The modification shown in Figs. 7 and 8 embodies my invention by the use of wire which is not insulated, the electrical insulation being otherwise properly provided, as 120 on the adjacent faces of the end cap. In this modification as illustrated in Figs. 7 and 8, a layer 28, facing, etc., of insulation is applied to the inner face of the end cap 16, and also at 28a about at least a portion of the inner face of the cylindrical flange of the end cap 16, the wire switch member 19 in this instance being without insulation. The insulation 28a also extends within the marginal outline of the slot 17 of the end cap 130

16, to thereby hold and insulate the wire switch member 19 when in its open-circuit position. When the wire switch member 19 is in its closed-circuit position, it engages the electrically conducting material of the end cap 16.

The modification shown in Figs. 7 and 8 also illustrate another arrangement of frictionally positioning the body of the wire switch member 19 interiorly of the end cap 16, without the use of lugs, recesses, etc., the wire switch member 19 in this instance being bent in spiral fashion, its bends engaging the insulation 28a on the interior of the cylindrical face of the end cap 16.

For the testing of the integrity of fuses, electrical bulbs, and other suitable electrical articles, the exterior end 18 of the switch member is set in its open-circuit position and the article to be tested, such as a cartridge fuse 30 indicated in Fig. 1 in dot-and-dash line, is placed in any suitable manner to have its one terminal 30a engage the exposed exterior portion 18 of my switch member and its opposite terminal 30b engage the metal of the flashlight casing or end cap. In the condition of integrity of the fuse or other electrical article, the bulb 12 of the flashlight is lighted. The non-lighting of the flashlight bulb 12 is proof of the non-integrity of the tested electrical article. It will be appreciated that with any electric bulb, fuse plug, etc., to be tested, the central terminal of the same is placed in contact with the exposed exterior end 18 of my switch member and the exterior metal terminal in direct engagement with the metal of the end cap 16.

Whereas, I have described my invention by reference to specific formations thereof, it will be understood that many changes and modifications may be made without departing from the spirit of the invention.

I claim:

1. A switch for a flash light or the like provided with a casing in whole or in part of electrically conducting material and enclosing one or more electric cells, and including an end cap, comprising in combination a movable switch member of resilient electrically conducting material extending interiorly of and insulated from the flash light casing and having an inner portion thereof exposed to engage and electrically contact with a cell casing, an end of said switch member extending exteriorly of the flash light casing for manual operation, a portion of said exterior end being exposed for electrical connection with the flash light casing for its closed-circuit position, and means for engaging and retaining said movable switch member in its open-circuit position whereby said exposed portion of the outer end of said member is out of electrical connection with the flash light casing.

2. A switch for a flash light or the like pro-

vided with a casing in whole or in part of electrically conducting material and enclosing one or more electric cells, and including an end cap, comprising in combination a movable switch member of resilient electrically conducting material extending interiorly of and insulated from the flash light casing and having an inner portion thereof exposed to engage and electrically contact with a cell casing, an end of said switch member extending exteriorly of the flash light casing for manual operation, a portion of said exterior end being exposed for electrical connection with the flash light casing for its closed-circuit position, and means for engaging and retaining said movable switch member in its open-circuit position whereby said exposed portion of the outer end of said member is out of electrical connection with the flash light casing, said electrical connection of said switch member at its closed-circuit position being effected by the resiliency of the material of said movable switch member.

3. A switch for a flash light or the like provided with a casing in whole or in part of electrically conducting material and enclosing one or more electric cells, and including an end cap, comprising in combination a movable switch member of resilient electrically conducting material extending interiorly of and insulated from the flash light casing and having an inner portion thereof exposed to engage and electrically contact with a cell casing, an end of said switch member extending exteriorly of the flash light casing for manual operation, a portion of said exterior end being exposed for electrical connection with the flash light casing for its closed-circuit position, a disk disposed within said flash light casing to which said movable switch member is fulcrumed, and means for engaging and retaining said movable switch member in its open-circuit position whereby said exposed portion of the outer end of said member is out of electrical connection with the flash light casing.

4. A switch for a flash light or the like provided with a casing in whole or in part of electrically conducting material and enclosing one or more electric cells, and including an end cap, comprising in combination a movable switch member of resilient electrically conducting material extending interiorly of and insulated from the flash light casing and having an inner portion thereof exposed to engage and electrically contact with a cell casing, an end of said switch member extending exteriorly of the flash light casing for manual operation, a portion of said exterior end being exposed for electrical connection with the flash light casing for its closed-circuit position, a disk disposed within said flash light casing to which said movable switch member is fulcrumed, and means for engaging and retaining said movable switch member in its

- open-circuit position whereby said exposed portion of the outer end of said member is out of electrical connection with the flash light casing, said electrical connection of said 5 switch member at its closed-circuit position being effected by the resiliency of the material of said movable switch member. 70
5. A switch for a flash light or the like provided with a casing in whole or in part of 10 electrically conducting material and enclosing one or more electric cells, and including an end cap, comprising in combination a movable switch member of resilient electrically conducting material extending interiorly of and insulated from the flash light casing 15 and having an inner portion thereof exposed to engage and electrically contact with a cell casing, an end of said switch member extending exteriorly of the flash light casing 20 for manual operation, a portion of said exterior end being exposed for electrical connection with the flash light casing for its closed-circuit position, a disk provided with a recess receiving said movable switch member 25 and thereby fulcruming the same, and means for engaging and retaining said movable switch member in its open-circuit position whereby said exposed portion of the outer end of said member is out of electrical 30 connection with the flash light casing. 80
6. A switch for a flash light or the like provided with a casing in whole or in part of electrically conducting material and enclosing one or more electric cells, and including 35 an end cap, comprising in combination a movable switch member of resilient electrically conducting material extending interiorly of and insulated from the flash light casing and having an inner portion thereof exposed to engage and electrically contact with a cell casing, an end of said switch member extending exteriorly of the flash light casing for manual operation, a portion of said exterior end being exposed for electrical connection with the flash light casing for its closed-circuit position, a disk provided with a recess receiving said movable switch member and thereby fulcruming the same, and means for engaging and retaining said movable 40 switch member in its open-circuit position whereby said exposed portion of the outer end of said member is out of electrical connection with the flash light casing, said electrical connection of said switch member at its closed-circuit position being effected by the resiliency of the material of said movable switch member. 90
7. A switch for a flash light or the like provided with a casing in whole or in part of 45 electrically conducting material and enclosing one or more electric cells, and including an end cap, comprising in combination a movable switch member of resilient electrically conducting material extending interiorly of and insulated from the flash light casing and having an inner portion thereof exposed to engage and electrically contact with a cell casing, an end of said switch member extending exteriorly of the flash light casing for manual operation, a portion of said exterior end being exposed for electrical connection with the flash light casing for its closed-circuit position, a disk provided with a recess receiving said movable switch member and thereby fulcruming the same, and means for engaging and retaining said movable 50 switch member in its open-circuit position whereby said exposed portion of the outer end of said member is out of electrical connection with the flash light casing, said electrical connection of said switch member at its closed-circuit position being effected by the resiliency of the material of said movable switch member. 100
8. A switch for a flash light or the like provided with a casing in whole or in part of electrically conducting material and enclosing one or more electric cells, and including an end cap, comprising in combination a movable switch member of resilient electrically conducting material extending interiorly of and insulated from the flash light casing and having an inner portion thereof exposed to engage and electrically contact with a cell casing, an end of said switch member extending exteriorly of the flash light casing for manual operation, a portion of said exterior end being exposed for electrical connection with the flash light casing for its closed-circuit position, a disk provided with a recess receiving said movable switch member and thereby fulcruming the same, and means for engaging and retaining said movable switch member in its open-circuit position whereby said exposed portion of the outer end of said member is out of electrical connection with the flash light casing. 110
